UNITED STATES PATENT OFFICE

WILLIAM J. BUTLER, OF CRANSTON, RHODE ISLAND, ASSIGNOR TO HENRY LEDERER & BRO. INC., OF PROVIDENCE, RHODE ISLAND, A CORPORATION OF RHODE ISLAND

POCKET LIGHTER

Application filed April 11, 1928. Serial No. 269,263.

This invention relates to a pocket lighter; and has for its object to provide a construction which may be easily and quickly assembled by friction fitting parts so that its 5 working parts may be disassembled without unsoldering.

A further object of the invention is the provision of friction means for removably holding the operating wheels in position.

10 A still further object of the invention is the provision of detachable frictionally secured means for blocking the removal of the friction and thumb wheels.

This invention further consists in the forming 15 of a sheet metal bottom plate by pressing operations to eliminate several steps heretofore necessary in the forming of the same.

With these and other objects in view, the invention consists of certain novel features of 20 construction, as will be more fully described, and particularly pointed out in the appended claim.

In the accompanying drawings:

Figure 1 is a side elevation of a lighter constructed in accordance with this invention.

Figure 2 is a top view thereof.

Figure 3 is a fragmental sectional view thru the spark producing mechanism mounted on the top of the fuel reservoir.

30 Figure 4 is a side elevation of the friction and thumb wheels.

Figure 5 is a side elevation of the head securing pin.

Figure 6 is a sectional view of the tubular 35 post for rotatably supporting the wheels.

Figure 7 is a top view of a pyrophoric tube.

Figure 8 is a sectional view on line 8—8 of Figure 3.

Figure 9 is a blank for the bottom wall of 40 the fuel reservoir.

Figure 10 shows the same after the first pressing operation.

Figure 11 is a sectional view of the plate shown in Figure 10.

45 Figure 12 shows the plate after being pierced.

Figure 13 shows the same after the collar has been formed thereon.

Figure 14 is a sectional view of the plate 50 shown in Figure 13.

Figure 15 is a fragmental section of the bottom part of the fuel reservoir showing the closure plug in position.

It is found in practice desirable to occasionally remove the operating wheels from 55 their positions in a pocket lighter, and in order to mount the wheels in such a way that this may be easily and readily accomplished without the necessity of disconnecting the soldered parts, I have mounted these wheels

on a tubular post and positioned a headed 60 friction pin in the bore of the tubular post to prevent removal of the friction wheel therefrom; and in order to further prevent removal of the parts in case the 65 friction and thumb wheels are separate elements, I have used a press fit for positioning the pyrophoric tube in a horizontal bore

of its support with the end of the tube extending over the thumb wheel to prevent the 70 same from lifting from the lighter and have also knurled or roughened one of the contacting surfaces between the bore and pyrophoric tube to more firmly secure the same in position. Further, in forming the bottom 75 wall of the fuel reservoir the same has heretofore been made of comparatively heavy stock and struck with a drop hammer or the like to draw the stock into position required for providing a thread-receiving portion to retain

the closure plug in position and then drilling or reaming out the bottom surface to provide 80 a recess for the head of the closure plug, and in order to avoid these expensive operations, I have formed the bottom plate of thin sheet 85 stock and pressed the same into position to receive the threads and head of the closure plug thereby eliminating the more expensive drop hammer and drilling or reaming operations

above described; and the following is a detailed description of the present embodiments of this invention and illustrating one construction by which these advantageous results may be accomplished:

With reference to the drawings, 16 is the fuel reservoir having a top plate 17 and a bottom plate 18. Upon the top plate there is mounted a trunnion post 19 having a tubular upper part formed by a bore 20 extending

thereinto. A collar 21 is formed to provide a 95

90

95

100

shoulder to engage the top plate 17 when inserted thereinto and soldered as at 22, as illustrated in Figure 3, to secure the same in upstanding position on the top wall.

5 The friction wheel 23 and thumb wheel 24 are here illustrated as formed in a single unit altho for the purpose of this invention they may be separate so long as they are so connected as to function together. These wheels 10 are rotatably mounted on the post 19 and prevented from lifting from position by the head 26 of a friction pin 25 which is positioned in the bore 20. This pin member has any desirable press fit connection with the bore 20. I have illustrated the shank 25 of 15 the pin being tapered to more firmly engage the side walls of the bore 20 as it is pressed into position. The post 19 is of a length slightly longer than the combined axial dimensions of the two wheels so that the head 26 may engage the top of this post without binding the wheels and preventing rotation.

20 The support 27 is suitably secured to the top wall of the reservoir and provided with a horizontal bore 28 thru which the pyrophoric tube 29 extends and frictionally engages therewith to hold the same in the desired position.

25 In order to increase the frictional engagement between the bore 28 and the tube 29 I roughen one of these parts preferably the tube 29 as at 30 to cause a firmer and tighter fitting of the parts as forced into position by sufficient pressure. The end 31 30 of this tube is positioned in proximity to the friction wheel 23 and extends above the thumb wheel 24 so as to prevent the thumb wheel from being removed from position until the pyrophoric tube 29 is forced back 35 thru its bore 28 to permit such removal. The usual pyrophoric material 32 is positioned in the tube 29 and forced by means of a spring 33 and thumb screw 34 into engagement with the friction wheel to secure the 40 desired pressure thereagainst.

45 In case it is desired to remove the wheels from the lighter it will, of course, be understood that the pyrophoric tube is first forced back in the bore 28 and the tapered plug 50 25 is withdrawn from the tubular support which permits removal of the wheels for repair or replacement after which the plug may be returned to position and the pyrophoric tube returned to its position in the 55 reassembly of the device.

The usual wick 35 with a closure cap 36 is provided for ignition and snuffing out as desired.

60 The bottom wall of the reservoir is formed of sheet stock shown as a blank 37 in Figure 9 and which, by means of a press, is formed into the shape illustrated in Figures 10 and 11 having a recessed part 38 to receive the head of the closure plug 39 and also with 65 flanges 40 for fitting over the fuel tank of

the device. The bottom plate is then pierced as at 41 and the stock about this piercing rolled to enlarge the opening and at the same time provide a collar 42 which is internally threaded as at 43 to receive the threads 44 of the closure plug to hold the plug in position and tightly seal the reservoir and prevent evaporation of the volatile fuel therefrom.

70 The foregoing description is directed solely towards the construction illustrated, but I desire it to be understood that I reserve the privilege of resorting to all the mechanical changes to which the device is susceptible, the invention being defined and limited only by the terms of the appended claim.

75 I claim:

80 In a pocket lighter, a fuel reservoir, a tubular post upstanding from said reservoir, a combined friction wheel and thumb wheel element rotatably mounted on said post, a pin frictionally engaging the bore of said post and having a head projecting over said wheel element to lock the same on said post, a vertical standard on said reservoir having a transverse bore, and a pyrophoric tube 85 frictionally engaging the transverse bore and having its end extending over the thumb wheel to additionally lock said wheel element on said post.

90 In testimony whereof I affix my signature.

95 WILLIAM J. BUTLER.
